UNITED STATES PATENT OFFICE.

GEORGES GALLAY, OF LE SENTIER, SWITZERLAND.

LEVER ESCAPEMENT.

Application filed January 5, 1920. Serial No. 349,550.

To all whom it may concern:

Be it known that I, GEORGES GALLAY, citizen of the Swiss Republic, residing at Le Sentier, Canton of Vaud, Switzerland, have 5 invented certain new and useful Lever Escapements, of which the following is a specification.

In lever escapements hitherto manufactured and which are said to be "normal" the pivoting center of the lever or anchor-shaped piece is at the intersection of perpendicular lines raised from each of the operating rays at the point where said rays cut the original circumference, so that in any case the ratio:

15

$$D = \frac{R}{\cos \alpha}$$

is to be found, in which ratio D =distance from the centers, R =the ray of the original circumference, α =the angle between the center-to-center line and the operating ray taken into account.

In some escapements, the aforesaid ratio varies for one of the angles owing to the 25 angle including the number of half teeth contained between the pallets, i. e. determined by the two operating rays, not being equal on each side of the center-to-center line. As a matter of fact, it is customary, 30 in making escapements with equidistant levers, to add, to one half of the insertion angle, on the side of the inlet pallet, an angle equalling one half of the angle made by the wheel at each oscillation of the anchor, which angle is subtracted from that 35 half obtained on the side of the outlet pallet. The result is that, as regards the operating ray pointing to said pallet, viz: forming with the center-to-center line, the smallest 40 of the two angles, the hereinbefore mentioned ratio

$$D = \frac{R}{\cos \alpha}$$

45 is no longer correct, as the unequal ratio

$$D > \frac{R}{\cos \alpha}$$

is correct. For the large angle, the ratio 50 obtained is

$$D < \frac{R}{\cos \alpha}$$

but it should be noticed that said angle is 55 larger than one half of the angle between the operating rays.

In all these normal lever escapements, the angles formed by the stop face of the pallet and the slope of the pallet face are different for each pallet. The angle of the inlet pallet is more acute than that of the outlet pallet. The consequence is that the outlet pallet is very sharp, hence very brittle. On the other hand, the necessity of having two kinds of pallets, complicates the jewel-setting of the levers and errors often occur, which errors cause the loss of the anchor.

60 The present invention,—which aims at obviating the aforesaid defects—relates to a lever escapement, the various parts whereof are so dimensioned as to secure the interchangeability of the pallets. The full lines of the single figure of drawings represents the escapement wheel bearing against the entrance impulse tooth and the dotted lines 70 in the drawing represents the position of said wheel and pallet when the said wheel bears against the outlet impulse tooth.

75 The point O_2 represents the position of the center of rotation of the anchor in the usual escapement as heretofore constructed; this point O_2 is, as already known, the point of intersection of the tangent lines $A O_2$, $B O_2$, of the wheel at points A and B. $O O_2$ is the bisecting line of the angle $A O B$. There is 80 no geometrical formula for finding the point O_1 . The point O_2 is found as heretofore and the location of the point O_1 was the result of experimental researches.

85 The advantages of such construction are 90 obvious: Errors in jewel-setting are done away with and the pallets are cheaper, as there is practically no waste of outlet pallets; besides, since the pallets are interchangeable the stocks of pallets at the watch-jobbers' 95 are reduced by half.

To obtain such pallets, one may, for example, assume the distance between the pivoting centers of the escape wheel and of the anchor to be longer than the original 100 ray of the lever wheel divided by the cosine of one half of the angle between the two operating rays.

In the drawings are shown, by way of example, an escapement the wheel of which 105 has fifteen teeth, two and a half of said teeth being engaged in the anchor.

In the escapement shown the center of the escape wheel is at O and that of the anchor pivot at O^1 . The operating rays are 110 designated by OA and OB . The latter do not include between themselves an integer

of half-teeth. The sum total of the angles α and B is but $59^\circ 38'$, whereas, in a normal escapement, said angle, in the case of like dimensions of construction, should be 60° and should include exactly five half-teeth. The rest of the escapement is constructed in accordance with the rules usually admitted for normal escapements with the difference that the length O O¹ is larger than

$$10 \quad \frac{OA}{\cos \alpha}$$

The result is that the straight lines connecting the stop or rest points with the pivoting centers of the anchor are not tangent to the original circumference of the escape wheel and therefore are not perpendicular to the operating rays OA and OB. Therefore, on the one hand, with reference to the inlet 15 pallet, the angle formed by the stop or rest plan and the slope is wider than in ordinary constructions and, on the other hand, with reference to the outlet pallet, the angle constituted by the same parts, is much more 20 acute.

In an ordinary construction of escapement the pivoting center of the anchor is determined by the intersection of the perpendicular lines raised on each side, from the operating rays. This construction, besides, renders it possible to notice that said operating rays are not equally distant from the center-to-center line. Moreover, these rays do not enclose a full member of half-teeth. 25 With such improvements, practically equal drops or falls may be secured, which otherwise could not be obtained. In such construction the distance of the centers is equal to the ray of the original circumference, i.e. to that which passes the foremost point of the tooth, divided by the cosine of the angle between the operating ray and the center-to-center line. It is easy to notice that, in the escapement made according to 30 the invention, (and shown in the drawings) the distance O¹ O = D is longer than in a normal escapement and this is true for all escapements constructed in view of using interchangeable pallets, that is pallets which 35 may practically differ from each other, beyond the usually admitted tolerance of a few minutes, but which, theoretically, are identical.

In normal lever escapements, the anchor 40 whereof encompasses two and a half teeth of a fifteen tooth wheel, the ratio is:

$$60 \quad \frac{2R}{D} = 2 \cos \alpha = 1.73206;$$

this ratio becomes : 1.81262 should the wheel bear eighteen teeth. In an escapement according to the invention, the aforesaid ratio is 1.65 for the fifteen tooth wheel and 1.70 for the eighteen tooth wheel.

65

I claim as my invention:

1. A lever escapement having interchangeable pallets in the plane of the lever, an escape wheel so situated relative to the lever that the distance between their pivotal centers is greater than the original ray of the wheel divided by the cosine of one half the angle included between the two operating rays.

2. A lever escapement mechanism comprising an escape wheel and an anchor, said anchor having interchangeable pallets, the characteristic features being that the distance between the pivoting centers of the escape wheel and the anchor is longer than the original ray of the lever wheel divided by the cosine of one half of the angle included between the two operating rays.

3. A lever escapement mechanism comprising an escape wheel and an anchor, said anchor having interchangeable pallets, the characteristic feature being that the distance between the pivoting centers of the escape wheel and the anchor is longer than the original ray of the lever wheel divided by the cosine of one half of the angle inserted by the two operating rays, the number of half-teeth included between the pallets expressed by being an integer and a fraction.

4. A lever escapement mechanism comprising an escape wheel and an anchor, said anchor having interchangeable pallets, the characteristic feature being that the distance between the pivoting centers of the escape wheel and the anchor is longer than the original ray of the lever wheel divided by the cosine of one half of the angle inserted by the two operating rays, the maximum of the ratio
